FRANK R. WEST, OF DETROIT, MICHIGAN, ASSIGNOR TO COPELAND PRODUCTS, INC.,
A CORPORATION OF MICHIGAN

PUMP FOR REFRIGERATING APPARATUS

Application filed June 23, 1928. Serial No. 287,852.

This invention relates to refrigerating apparatus. It has to do particularly with a novel and extremely compact compressor mechanism, and a novel method and apparatus for supplying motive power to the compressor together with a novel manner of conducting the refrigerant to and from the compressor structure.

In the mechanical refrigeration art, it has been the general practice to utilize a compressor, as a unit in a refrigerating system, and such compressors, while more or less efficient during the first few months of operation, have presented important difficulties after continued service. Such difficulties have been due mainly to the necessity of a rotating seal to prevent the escape of refrigerant from the compressor housing. It has been the usual practice to utilize approximately an 80 pound spring to keep the stationary seal and shoulder on the crank shaft in sealing contact, and due to this spring, it has heretofore been necessary to limit the speed of the compressor to approximately 325 to 400 R. P. M. in order to reduce the wear between such parts. Furthermore, the compressors of the prior art have been provided with thrust bearings, connecting rod bearings, and other parts which of necessity have required accurate and expensive machining.

It is the object of the present invention to completely eliminate the rotating seal or joint of the prior art and to replace the same with a non-rotative flexible sealing member which will last the life of the compressor and permit any speed desired. More specifically, the present invention contemplates the supplying of motive force to the reciprocable piston or pistons by means of an oscillating member, the entrance of which into the cylinder housing, or crank case housing, is sealed by means of a non-rotative and permanently fixed bellows or flexible sealing member. With this construction, there is no rotating bearing in the compressor itself, and practically no parts which will cause knocks due to wear. The bearings in the compressor housing are merely oscillating pivot bearings, requiring no particular accuracy in

manufacture or assembly, and which will be very quiet in operation over a long period of time.

A further feature of the present invention resides in the design and compact arrangement of parts whereby the power transmitting means and the compressor form a unitary structure so constructed as to eliminate belts, fly wheels, motor pulleys, etc. In combination with this compact assembly, the present invention contemplates the use of ported intakes, together with an increased compressor speed. This novel manner of operation not only permits less starting effort and the use of an electric motor having a minimum starting torque, but also greatly increases the efficiency of the compressor at high speeds.

Various other features will be brought out in the specification and claims.

In the drawings:

Fig. 1 is a vertical sectional view taken mainly on line 1—1 of Fig. 2.

Fig. 2 is an end elevation, partly in section, taken on line 2—2 of Fig. 1.

Fig. 3 is a plan view, partly diagrammatic and partly in section, and showing in particular the preferred relation of the novel compressor unit with the remainder of the refrigerating system.

Fig. 4 is an enlarged fragmentary detail view, showing the manner of connecting the operating lever to the cylinder structure.

Fig. 5 is a fragmentary sectional view taken on line 5—5 of Fig. 4.

The structure embodied in the present invention is quite radical from standard compressor design, and while similar terms may be used in some instances in describing the design and arrangement of the parts thereof, it will be understood that such terms apply specifically to the present construction rather than to the generally accepted parts of standard compressor design.

The present invention is particularly adapted to two-cylinder compressor design, inasmuch as two cylinders can be utilized for very little addition in expense. In Fig. 1 I have shown a two-cylinder compressor structure, comprising the two horizontally

positioned cylinders 1 and 2. These cylinders are adapted to position and receive an integral double acting piston, consisting of the pistons 3 and 4 and the integral connecting portions 5.

5 This integral piston structure is reciprocated horizontally by means of an actuating lever or arm 6 which is connected to the spaced members 5 of the pistons by means of a suitable pin 7. The upper end of the operating arm 6 is preferably bifurcated and constitutes a cross head for a sliding shoe block element 8. It will be obvious that as the arm 6 slides back and forth that the pistons 3 and 4 will be horizontally reciprocated and that there will be a very slight sliding action between the block 8 and the upper end of the arm 6, whereby the pin 7 merely acts as a pivot pin and does not absorb any severe impacts.

20 The actuating arm 6 is preferably integrally connected to a power arm or lever 9, and this unit comprising the operating lever 6 and the power lever 9 is preferably pivoted as at 10 and 11. The upper end of the lever 9 is slidably connected as at 12 with a strap member 13 which forms a part of an eccentric mounting for the end of the motor shaft 14, the motor being generally designated 15. It will thus be obvious that I preferably utilize a direct drive and that oscillating movement is imparted to the power arm 9 by reason of the eccentric strap unit 13.

25 The compressor or cylinder housing may be generally designated 16 and such housing comprises the cylinders 1 and 2, the gas receiving chamber 17 and the downwardly extending chamber 18. Secured to the lower end of this chamber 18 is an annular ring 19 adapted to positively seal or position the inner end of a bellows member 20. In other words, the inner annular end of the bellows 20 is securely held in place by the annular ring 19 whereby to present a positive non-rotating seal. The operating lever 6 terminates in an enlarged or up-set end 21 which forms an annular flange for receiving the other end of the bellows 20, such other end of the bellows 20 being positively held in sealing position by means of a second annular ring 22, which is securely bolted to the flange 21.

30 The bellows 20 is preferably so positioned, or in other words, the bottom of the chamber 18 and the flange 21 of the lever 6 are so positioned, that the opposite ends of the bellows member are equally distant from the center line of the pivots 10 and 11. It will thus be obvious that although the bellows 20 is subjected to very little flexing during operation of the compressor, that the flexing that does take place will be localized at the central part thereof, whereby to insure permanence of the bellows member. The flexing of the bellows is further reduced to a

minimum by reducing the distance of travel of the pistons, which is primarily due to the increased R. P. M. as will be later explained.

35 The housing for the power arm 9 as well as the lower end of the operating arm 6 is preferably formed integrally with the compressor housing 16. This produces a very compact and inexpensive casting, and such housing need not be accurately machined as it only contains three pivots 10, 11, and 14, which are merely oscillating pivots. Very little oil is required in a compressor of the present design, and the entire compartment 18 may be filled with oil up to a point where it may be utilized as a lubricant for the pistons 3 and 4.

40 Due to the non-rotative flexible sealing joint it is possible to increase the speed of the compressor to approximately 900 R. P. M., although motors having a standard R. P. M. of 1700 to 1800 R. P. M. can be used, and in this event the compression space in the cylinders is preferably reduced.

45 In direct combination with this increased speed, I preferably introduce the refrigerant into the compressor at the point 17 and this refrigerant is alternately fed into each cylinder by means of the ports 30 and 31, such ports being uncovered by the end of the piston at one end of the stroke. Separate intakes could be provided in each cylinder wall for each piston, and thus eliminate the passing of the refrigerant above any body of oil. It will also be obvious that intake valves similar to the discharge valves shown could be installed in the heads of the pistons, as in standard practice. However, I prefer to use the ports as this offers a material advantage in that less starting effort has to be exerted by the power means, when bringing the compressor up to speed. This is due to poor volumetric efficiency until maximum piston speed has been attained, as at low speeds there will be considerable gas flow losses through the ports. If the compressor were operated at a low R. P. M. it is obvious that a certain percentage of trapped gas would be allowed to escape back, thus leaving only a partial amount of gas to be compressed, requiring less power than when up to speed.

50 When the compressor has increased to full speed, say approximately 900 R. P. M. the higher piston speed and gas velocity will give the in-going gas a positive inertia which prevents its backing up before the piston shuts off the port. It will be obvious that this use of ported intakes permits the use of an electric motor having a minimum starting torque. This increase in R. P. M. greatly increases the efficiency of the compressor and thus greatly increases the refrigerating effect so that the period of operation of the compressor will be greatly decreased.

55 In Fig. 1 I have shown the ends of the 130

cylinders 1 and 2 as being provided with suitable exhaust valves and exhaust valve housings 32 and 33, and the compressed gas may be conducted away by means of suitable conduits 34 and 35. In the partly diagrammatic showing in Fig. 3 the exhaust conduits from the compressor housing are shown as joining at the front of such housing as at 36 from where all the compressed gas is conducted to the condenser in the usual manner.

Not only is the flexing of the bellows materially reduced by increasing the R. P. M. and shortening the stroke of the piston, but such flexing is also materially reduced by increasing the length of the power arm. This long power arm also reduces side wear of the piston and cylinders. It will be obvious that other modes of power transmission between the motor and the operating lever 6 may be utilized but for extreme compactness, simplicity, and ease in assembly, the present showing is the preferred one.

It will be understood that the crank housing may be provided with suitable cover plates at the ends of the stub shafts 10 and 11, whereby the housing may be filled with oil up to a point adjacent the shaft 14.

What I claim is:

1. A unit for a refrigerating system, comprising a reciprocable piston, a housing therefor, a member connected to said piston and extending through said housing at an angle approximately a right angle to said piston, and a flexible sealing means positioned around said member and the opening in the housing and being positively secured at one end to said housing and at the other end to the end of said member, said member being pivotally mounted at points external of said flexible sealing member and the axis of said pivotal mounting passing substantially through the center of said sealing member.

2. A unit for refrigerating systems, comprising a cylinder housing, a piston mounted therein for reciprocation, an oscillatable operating arm connected to said piston and extending through said housing, a non-rotatable flexible seal connected to an end of said arm and said housing for sealing the housing, a power arm integrally connected to said operating arm and extending parallel thereto and in the same direction from the axis of oscillation of said operating arm, a rotatable operating means connected with said power

arm in such a manner as to cause oscillation thereof, the oscillation of said power arm in turn causing oscillation of said operating arm and reciprocation of said piston, the movement of said operating arm being absorbed by the flexibility of said seal, and said flexible seal being so positioned between said arm and said housing that the flexing thereof will take place about an axis intermediate the ends.

3. A unit for refrigerating systems, com-

prising a cylinder housing, a piston reciprocable therein, a member for reciprocating said piston and extending through said housing, a non-rotatable sealing member connected with said housing and said actuating member, and power means for actuating said member adapted to be operated at a relatively great speed and a port in the wall of said cylinder controlled by said piston for admitting the fluid to be compressed.

4. A unit for refrigerating systems, comprising a double cylinder housing with opposed cylinders, integrally connected pistons for said cylinders, an oscillatable operating member pivotally connected to said pistons in such a manner as to permit positive longitudinal movement of the pistons and said pivot point, said member extending through said cylinder housing, a non-rotatable flexible sealing member connected to one end of said member and said housing, and means externally thereof for oscillating said member to cause reciprocation of said piston, said oscillation being about an axis passing through and intermediate the ends of said sealing member.

5. A unit for a refrigerating system, comprising a cylinder housing containing a reciprocable piston, a member pivotally mounted at one end at a point remote from the piston and extending through said housing for reciprocating the piston, and a flexible cylindrical sealing member connected at one end to said housing and at the other end to said pivoted end of said member, said sealing member being so positioned that the axis of said pivotal mounting will be centrally of and equidistant from the ends of said sealing member.

6. A unit for a refrigerating system, comprising a compressor housing having a reciprocable piston therein, and including a chamber, extending at right angles to said piston, a second chamber extending laterally from the outer end of the first chamber, an arm pivoted at one end extending through said first chamber and connected at one end to said piston for reciprocating the same, and connected at the other end to a shaft positioned in said second chamber, and a bellows member within said second chamber and directly secured to said housing and to the pivoted end of said arm for sealing the first chamber from the second chamber.

7. A unit for a refrigerating system, comprising a reciprocable piston, a housing therefor, a member pivotally mounted at one end and connected at its opposite end to said piston and extending through said housing at an angle approximately at right angles to said piston, and a flexible sealing means positioned around the first mentioned end of said member and the opening in the housing and being positively secured at one end to said housing and at the other end to the end of

said member, the axis of movement of said member being intermediate the ends of said sealing means.

8. A unit for a refrigerating system, comprising a reciprocable piston, an oscillatable member connected to and extending at an angle approximately at right angles to said piston, a housing for said unit including a cylinder housing, a chamber extending at substantially right angles to said cylinder housing and enclosing said member, and an additional chamber extending transversely at the end of said first chamber all formed as an integral unit, means positioned in said second chamber for causing oscillation of said member, and a bellows member connected at one end to one end of said oscillatable member and at the other end to the housing at the joint between said first chamber and said second chamber.

9. A unit for a refrigerating system, comprising a reciprocable piston, an oscillatable member connected to and extending at an angle approximately at right angles to said piston, a housing for said unit including a cylinder housing, a chamber extending at substantially right angles to said cylinder housing and enclosing said member, and an additional chamber extending transversely at the end of said first chamber all formed as an integral unit, means positioned in said second chamber for causing oscillation of said member, and a bellows member connected at one end to one end of said oscillatable member and at the other end to the housing at the joint between said first chamber and said second chamber, the means in said second chamber for causing oscillation of said member being pivoted about an axis extending substantially through the central part of said bellows member.

In testimony whereof I affix my signature.
FRANK R. WEST.
